ARC-LAMP.

1,096,411.

Specification of Letters Patent. Patented May 12, 1914.

Application filed January 16, 1905. Serial No. 241,288.

To all whom it may concern:

Be it known that we, ANDRÉ BLONDEL, a citizen of the Republic of France, and GAËTAN DOBKEVITCH, a subject of the Emperor of Russia, both residing at Paris, France, have invented certain new and useful Improvements in Arc-Lamps, of which the following is a specification.

Our invention relates to the regulating 10 mechanism of arc lamps and is more particularly concerned with a regulating mechanism for luminous arc lamps.

In luminous arc lamps, as is well known, the electrodes usually contain minerals and 15 the operating distance between the electrodes is materially greater than that in ordinary arc lamps. In the operation of luminous arc lamps, products of combustion are evolved from the arc, which upon cooling, 20 tend to produce a light layer of non-conductive mineral matter upon the electrodes which obviously hinders the reformation of the arc.

The object of our invention is to provide 25 for regulating the feed of luminous arc lamps in such manner that when the arc is broken it can be reformed in minimum time so as to prevent the cooling of the mineral products from forming a non-conductive 30 layer on the electrodes, and afterward to more gradually regulate the feed of the electrodes while they are separated at substantially normal operating distance apart.

Further objects of our invention will be 35 apparent from the detailed description of an embodiment of the same which follows.

The principle upon which our invention is based is that when the arc becomes extinguished, the electrodes are rapidly brought 40 together again and drawn apart to a predetermined distance, after which the regulation is more gradual. This principle is utilized and the objects of the invention fulfilled by providing suitable feeding mechanism which is only slightly retarded when 45 the arc has become extinguished and while the electrodes are being separated to a predetermined distance apart, but which is more strongly retarded after the electrodes 50 have been drawn apart to the predetermined distance, which is substantially the normal operating distance apart.

To clearly illustrate the principle upon 55 which our invention is based and to enable others skilled in the art to understand and

practise the invention, we shall describe the same with reference to the accompanying drawings in which an embodiment of our invention is shown by way of example.

In said drawings Figure 1 is a front elevation of an arc lamp provided with our invention. Fig. 2 is a side elevation of the same. Figs. 3 to 6 are detail views of the train of gears; Figs. 7 and 8 are detail views of the releasing mechanism for the train of gears; Fig. 9 is a detail view of the escapement mechanism; Fig. 10 shows details of the train of gears assembled and the releasing device. Fig. 11 is a sectional elevation showing the arrangement of the dash-pot 70 and Fig. 12 is a bottom view of the dashpot.

Referring now more specifically to said drawings, 1 indicates a casing constituting a balance and carrying a train of gears. The gears referred to may consist of a permanently intermeshing train of wheels and pinions 3, 3', 4, 4', 5 and 5', the wheel 3 meshing with a pinion 3' on 4, the wheel 4 meshing with a pinion 4' moving with 5, and the wheel 6 moving in unison with the wheel 5 through the medium of intermeshing teeth on wheel 5 and on a pinion 5' carried on the axle-pin of wheel 6. The axle-pin of wheel 6 also carries the ratchet wheel 7. It will be seen in Figs. 1 and 6 that the wheel 3 is 80 connected with a chain 2 which transmits the motion to the electrode holders as will hereinafter appear. The casing 1 may be fulcrumed between upright bracket arms 13 and to facilitate its rocking movement any 85 desired arrangement of knife edge fulcrum may be provided.

An escape-lever 8 journaled at *d* and weighted at *f* (see Figs. 1 and 9) carries upon the axis *g* a small double lever *h* with 95 two small rollers *i* and *k*. A pendulum or other oscillatory stop device 9 is pivoted on the axis *a*, the axis being secured to the plate *b*. This plate is mounted on one side of the casing. The pendulum is provided with a pin *c*, which in one of the positions of said casing presses against the wheel 6, thereby preventing movement of the same. It will be seen that the pendulum thus acts as a yielding stop, and, after the pin on the pendulum has engaged the wheel 6, further movement of the casing produces a corresponding movement of the pendulum, the pendulum moving bodily with the casing. As soon as the left hand magnet attracts its armature 100

and thus rocks the balance to the left, the wheel 6 is released and the gears begin to move due to the weight of the upper electrode and connected parts, and the electrodes thus approach each other. During this operation the rollers *i* and *k* alternately engage the teeth of the ratchet wheel 7 and thus regulate the escapement, the weight *f* being rotated about its pivot. From the position 10 shown in Fig. 9, when the wheel 7 is rotating in the direction indicated by the arrow, the roller *k* would be lifted on the incline of the notch with which it is in engagement and the roller *i* caused to engage the second notch to the left. This roller will then be similarly lifted and the weighted lever, which oscillates about the pin *g* as a pivot, acts as an inertia device to regulate the movement of the clock gears.

20 At opposite sides of the sector-shaped box 1, we may provide suitable straps or chains 10, suitably attached to the box 1 and secured to the upper ends of two movable soft iron cores 11 forming plungers, which are 25 suitably disposed within the solenoids 12. One of the solenoids is connected in series with the arc circuit and the other in shunt thereto. When the arc becomes longer and its resistance increases, the shunt coil is energized more strongly and thus rocks the sector-shaped box to the left in Fig. 1. When the arc becomes shorter and its resistance thus decreases, the series coil is more strongly energized and the box 1 is rocked 30 to the right in Fig. 1. The effect of rocking the box 1 to the left in Fig. 1 is to draw the electrodes together, whereas the effect of rocking the box 1 to the right in Fig. 1 is to separate the electrodes farther. In order 35 to obtain this effect from the rocking of the box 1, the wheel 2, mentioned above, drives the depending chain 14 suitably guided by pulleys 15, of which one end is suitably connected with the upper electrode holder 16 40 secured at the lower end of rod 17, and the other end suitably connected with the rod 18, moving between the guides 19 and bearing the lower electrode holder 20.

With the mechanism thus far described, it 45 is apparent that the tendency of an elongation of the arc is to cause the electrodes to approach each other, whereas the tendency of a shortening of the arc is to cause the electrodes to recede from each other. A 50 shoe or friction contact device 22 is pressed by yielding strips 23 against the upper electrode near its contact with the lower electrode, and a friction contact device 24, influenced by a dropping lever, clamps the 55 electrode between 24 and a ring like frame 25. This form of friction contact device is especially advantageous in connection with the use of high resistance or mineralized electrodes. An economizer 26 surrounds the 60 point of the upper electrode, and a reflector 65

27 and protection cap 28, for keeping out the rain or air, are provided. 29 and 30 are respectively bottom and top plates of the lamp, and 32 is the suspending bracket therefor.

33 are columns supporting the upright brackets 13, and 34 are magnetic shells which may be placed around coils 12 to increase the attraction for the plungers.

In order to regulate the feed, we propose 75 to strongly retard the feed mechanism while the electrodes are at substantially normal operating distance apart, but to only weakly retard the feed mechanism when the arc has become extinguished, or when the electrodes are in contact with each other. In

order to effect this, various constructions are possible, but as an example of such, we have shown and shall describe a dash pot retard- 80

ing device. This dash pot is illustrated in 85 detail in Fig. 11. It will be seen that it comprises a casing 21 closed below by a bottom plate 36, and opening above through a plate 30. In this casing 21 is disposed a piston 37 which is connected as by rod 38 90

with the plunger in the shunt solenoid at the left in Fig. 1. Piston 37 is provided with a flap valve 39 and a reciprocatory valve 41, the latter having a tapered head seated in an inwardly tapering seat in the tube 40 of 95

the piston, and provided with a downwardly projecting stem 42 of such length as to engage the bottom plate 36 and hold valve 41 off its seat while the piston is in the lower portion of its stroke. By the employment 100 of these two valves, we are enabled to positively and effectually control the movements of the balance 1 in the necessary manner. Chains 35 and 36 support the lower and upper electrode holders respectively 105 when the electrodes are consumed.

Flap valve 39 regulates the movement of the piston while it is in the upper portion of its stroke and the valve 41 is closed, so that the feed is strongly retarded in that portion. 110

This portion of the piston stroke is during the time when the electrodes are at substantially normal operating distance apart. The valve 41, by reason of its elongated stem 42 striking the bottom plate 36, is maintained open while the piston is in the lower portion of its stroke (as when the arc is broken or the electrodes are together), and therefore, in that part of its stroke the piston may have a rapid movement and the retarding effect 115 upon the feed mechanism will be very weak.

When the upper and lower electrodes are together and the current is turned off, the balance is tilted to the left, by reason of the weight of the upper electrode holder, and 120 the piston 37 is in the lower portion of its stroke, the valve 41 then being held open by its stem 42 resting on the bottom plate 36. When the current is turned on the series 125 solenoid is strongly energized and the bal- 130

ance is tilted to the right, the first portion of this motion being very rapid due to the weak retarding effect of the piston because of the valve 41 being open. The dimensions and proportions are such that the piston will reach the position in which the valve 41 closes at about the time when the electrodes have been separated to a distance approximately corresponding with their normal operating distance apart, after which the continued rise of the piston and separation of electrodes will take place slowly until the current through the shunt solenoid (which becomes stronger as the arc lengthens and increases the resistance in the series circuit) reaches the value where its tractive effect upon the feed balances that of the series solenoid. Thereafter slight oscillations of the current through the arc will effect the exact adjustment as in ordinary series shunt feed controls. As the electrodes become consumed by operation, or should for any reason the arc become lengthened to the point of extinction, the series solenoid is at once deenergized, and the shunt solenoid receives an increment of current. The effect of this is to tilt the balance to the left by which the pendulum brake is rocked to free the train of gears, so that the electrodes are fed toward each other under the action of the weight of the upper electrode carrier, but this movement is slackened by the train of gears. When the valve stem 42 strikes the bottom plate 36 and opens the valve 41 the downward movement of the piston may be very rapid and thus permit the electrodes to be brought together in a very short time after the arc has become extinguished.

What we claim is:

1. In an arc lamp, a pair of coöperating electrodes on which non-conducting coatings are formed in operation, mechanism connected thereto for establishing the arc and regulating the same, and a retarding device connected with said mechanism which but slightly retards the movement of the electrodes when they are less than a predeter-

mined distance apart and strongly retards the same when they are at or beyond such distance apart. 50

2. In an arc lamp, a pair of coöperating electrodes which move together by gravity, a lever, means for rocking the lever, a system of gears connected to the electrodes and carried by said lever and so arranged as to separate the electrodes on movement in one direction, means responsive to the movement of the lever in the opposite direction for releasing the gears and permitting the electrodes to feed together, and a retarding device connected to said lever arranged to retard the movement of the lever but slightly within a predetermined range of movement and to retard it strongly beyond that range. 55

3. In an arc lamp, a pair of coöperating electrodes on which non-conducting coatings are formed in operation, mechanism connected thereto for establishing the arc and regulating the same, a retarding device connected with said mechanism which strongly 60 retards the action thereof when the electrodes are at substantially normal operating distance apart and which weakly retards the same when they are substantially less than said normal operating distance apart. 75

4. In an arc lamp, a pair of coöperating electrodes on which non-conducting coatings are formed in operation, mechanism connected thereto for establishing the arc and regulating the same, a dash pot connected 80 with said mechanism which strongly retards the action thereof when the electrodes are at substantially normal operating distance apart and which weakly retard the same when they are substantially less than said 85 normal operating distance apart.

In testimony whereof, we have signed our names to this specification in the presence of two subscribing witnesses.
